UNITED STATES PATENT OFFICE.

EDWARD BLAISE, OF BROOKLYN, NEW YORK.

CABINET FOR TALKING-MACHINE RECORDS.

1,394,964.

Specification of Letters Patent.

Patented Oct. 25, 1921.

Application filed September 18, 1919. Serial No. 324,422.

To all whom it may concern:

Be it known that I, EDWARD BLAISE, a citizen of the United States, and resident of the borough of Brooklyn, in the city and State of New York, have invented a new and useful Improvement in Cabinets for Talking-Machine Records, of which the following is a specification.

This invention relates to a cabinet for talking machine records, and has for an object to provide such a structure which includes means for very compactly holding a large number of records when out of use and for simply and quickly exposing the said records for separate withdrawal for use.

Another object consists in providing such a structure in which the records are held when out of use in flat horizontal position, and in substantial parallelism with each other; while the said records are presented for withdrawal in a substantially vertical position and fan-like arrangement.

Another object consists in providing such a structure which is relatively cheap and simple to manufacture, easy to operate and sightly in appearance.

A further object consists in providing certain improvements in the form, construction and arrangement of the several parts, whereby the above named and other objects may be effectively attained.

A practical embodiment of the invention is represented in the accompanying drawings in which,

35 Figure 1 represents a detail face view of the structure.

Fig. 2 represents a section taken in the plane of the line II—II of Fig. 1, looking in the direction of the arrows.

40 Fig. 3 represents a section similar to Fig. 2 but showing certain of the parts in different positions, and having certain parts broken away.

Fig. 4 represents a section similar to Fig. 45 3 but showing certain parts in different positions.

Fig. 5 represents a detail section taken in the plane of the line V—V of Fig. 2, looking in the direction of the arrows.

50 Fig. 6 represents a detail face view with the parts in open position.

Fig. 7 represents a section taken in the plane of the line VII—VII of Fig. 6, looking in the direction of the arrows.

Fig. 8 represents a section taken in the 55 plane of the line VIII—VIII of Fig. 6, looking in the direction of the arrows.

Fig. 9 represents a detail vertical section showing the parts at one stage of the opening operation.

Fig. 10 represents a view similar to Fig. 9 showing certain parts in different positions.

Fig. 11 represents an enlarged detail vertical section showing the envelop for holding the records.

Fig. 12 represents a section, on the same scale, partly broken away, taken in the plane of the line XII—XII of Fig. 11, looking in the direction of the arrows.

Fig. 13 represents an outside face view of the record envelop, on the same scale.

Fig. 14 represents a vertical section thereof, partly expanded, and on the same scale.

The structure includes an outer casing 75 which has a rear wall 1 and two side walls 2 and 3; the said casing being designed to serve as a chest or inclosure for a number of drawer-like elements embodying my invention. At different positions along the 80 insides of the walls 2 and 3, there are located slats 4, 5, which are horizontally disposed and which serve as tracks to support the drawer-like elements. These slats may be screwed to the walls of the casing as clearly 85 shown in Figs. 8 to 10.

The drawer-like elements which embody my invention are thus arranged in a vertical series in the casing, which latter may be designed to accommodate any desired number 90 of the said elements; and, as the said elements are all exactly alike, it will suffice to describe one of them only. The said elements include a member which I call the drawer and a member which I call the receptacle.

95 The drawer is composed of two side members 6, 7, a rear member 8, two longitudinal bottom members 9, 10, and two cross bottom members 11, 12. The arrangement of the 100 said members is clearly shown in the drawing and it will be understood that they may be secured together in any desired manner so as to constitute a drawer of skeleton formation. The cross bottom members 11 and 12 lie in a plane below the longitudinal bottom members 9, 10, and are designed to rest 105 and travel upon the slats 4, 5. The said

slats are let into the side members 6, 7 (as clearly shown in Fig. 5) so as to enable each drawer to lie in contact with the drawers above and below it, for the purpose of economizing space, and it will thus be seen that the cross members 11, 12 of each drawer are arranged to slide upon the side members of the drawer below as well as on a pair of the slats 4, 5.

10 The front of the casing 1, 2, 3, has a series of cross pieces 13 that are horizontally arranged and let into notches 14 formed in the sides 2 and 3 so as to be flush with the front of the said sides. These cross pieces are arranged so that one will lie between each pair of drawers and they are located in the same planes as the bottom cross members 11, 12 of the drawers, and held in place by moldings 13*. The result of this arrangement is that, 15 when a drawer is pulled forward on the slats 4, 5 its outward movement will be terminated by the contact of its cross member 11 with a cross piece 13, as clearly shown in Fig. 8. The parts just named are so located 20 as to stop the outward movement of the drawer when it protrudes about half its length from the casing.

The receptacle comprises a front member 15 and two side members 16, 17 which are 25 hinged to the member 15 as clearly shown at 18, 19, so as to provide an articulated receptacle which has the capacity of opening in a fan-like manner. The front member 15 of the receptacle may be composed of wood, like 30 the drawer and casing, but the side members 16, 17 may conveniently be pressed from sheet metal and their lower edges rolled into knuckles for the reception of the pintles of the hinges 18, 19, which pintles also enter 35 complementary knuckles formed in metallic bands 20 that are secured to the front member 15.

The upper edges of the side members 16, 17 are crimped over so as to house offset 40 rods 21, 22, the ends of which rods are out of line with the body portion thereof and pass through flanges 23, 24 formed integral with, and projecting at right angles from, the side members, 16, 17. This arrangement 45 prevents the rods 21, 22 from turning in the members 16, 17. The protruding ends of the rod 22 enter grooves 25, 26 formed in the inner faces of the side members 6, 7 of the drawer. These grooves 25, 26 are straight, 50 lie adjacent the bottom of the drawer, and extend from the rear of the drawer a little more than one half of the distance toward the front thereof. The protruding ends of the rod 21 enter grooves 27, 28 that are also 55 fashioned in the inner faces of the side members 6, 7. These grooves 27, 28 extend from the rear of the drawer to a point adjacent the front thereof and are of such contour that the rear portions thereof lie in parallelism but above the grooves 25, 26, while the 60

front portions expand outwardly and forwardly. The precise shape of these grooves 25, 26, 27, 28 is clearly shown in Figs. 8 to 11 inclusive. The said grooves may be conveniently formed by screwing properly shaped ribs or cleats 29, 30 to the inner faces of the side members 6, 7.

The size and shape of the front member 15 of the receptacle corresponds substantially with the cross sectional size and shape of its drawer, while the distance from the front ends of the grooves 25, 26 to the front ends of the grooves 27, 28 is much greater than the height of the said member 15, with the result that, when the rods 21, 22 rest in the front ends of their complementary grooves, the side members 16, 17 of the receptacle will be opened in a fan-like manner.

From the foregoing description it will be seen that the receptacle 15, 16, 17 may be housed within its drawer by moving the rods 21, 22 along toward the rear ends of their respective grooves, as clearly shown in connection with the lower drawer represented in Fig. 8. This movement of the rods 21, 22 causes the side members 16, 17 to be drawn toward each other until they lie in substantial parallelism with each other and, in this position of the parts, the front member 15 of the receptacle serves as the front of its drawer. The said member 15 has a convenient handle or knob 31 and, in order to open the parts, it is merely necessary to seize this handle and pull forwardly. This act will first move the receptacle forwardly in its 100 drawer until the rod 22 abuts against the front ends of the grooves 25, 26, as shown in dotted lines Fig. 9. Continued forward pulling will move the drawer forwardly until its bottom cross member 11 contacts with the complementary cross piece 13, as shown in full and dotted lines Fig. 10. At this stage

it is merely necessary to let go of the handle 31 of the receptacle which swings downwardly under the influence of gravity, until it depends from and substantially at right angles to its drawer. This movement of the receptacle will automatically cause the rod 21 to travel forwardly and downwardly in the grooves 27, 28 and thus open the side members 16, 17 of the receptacle. In case the rod 21 does not move all the way to the front of its grooves, this may be accomplished manually. In returning the parts to their closed position it is merely necessary to seize the handle 31 and swing the receptacle forwardly and upwardly until the rod 21 is passed along in the grooves 27, 28, to a position substantially above the rod 22, as shown in Fig. 10. Stops 17* at each side of the member 17 are designed to engage recesses 6* in the bottom of the drawer to limit the upper swinging movement of the receptacle. Then the handle 31 is pushed inwardly, reversing the operations described in connec- 130

tion with opening the parts, until the receptacle is completely housed within the drawer and the drawer within the casing.

As a result of offsetting the rods 21, 22 it will be seen that, when the parts are in open position shown in Fig. 8, the receptacle 15, 16, 17 is slightly elevated in its drawer. This effects a slight economy of space by enabling it to be built lower to the floor without the danger of the lowermost receptacle hitting the latter when in its pendant position.

My invention also includes an envelop for holding a plurality of records within the receptacle, and the construction of this envelop and its connection with the other parts of the structure are clearly shown in Figs. 11 to 14.

This envelop may be composed of stiff paper, card board, or the like and have two sides 32, 33 that are substantially the same size and shape as the side members 16, 17 of the receptacle. The upper edges of the sides 32, 33 are intended to be slipped under snap springs 34, 35 that are carried by the rods 21, 22 and yieldingly bear against the inner surfaces of the side members 16, 17. The envelop also includes a number of pockets 36 that are connected with the sides 32, 33 and with each other. The connection of these pockets 36 with the sides 32, 33 is made at the side and bottom edges; while the connection of these pockets with each other is also made at the top edges, one side of each 35 pocket being secured to the adjacent side of the next pocket, and so on. Suitable reinforcing material, such as fabric, may be applied to the pockets by an adhesive at any desired point of connection, and I find it preferable to use this reinforcing material at the top edges of the pockets in order to take up wear incident to the insertion and removal of the records. In brief, the connection of the pockets 36 with each other and 45 with the sides 32, 33 may be described as an accordion plait arrangement permitting the envelop to be expanded or contracted at will.

The pocket is inserted in the receptacle 15, 16, 17, as clearly shown in Fig. 11 and, 50 as its sides 32, 33 are secured to the side members 16, 17 of the receptacle, the envelop will open in a fan-like arrangement together with the receptacle. A record 37 may be placed in each of the pockets 36 so that, when the envelop and receptacle open 55 the upper edges of the records 37 will be readily exposed for the withdrawal of the records, while the records will be held in the envelop and receptacle in the fan-like arrangement mentioned and clearly shown in Fig. 11.

The upper corners of the pockets may be cut away, as clearly shown in Figs. 12 and 13, in order not to interfere with the spring 60 clips 34, 35.

This fan-like opening of the envelop causes the lower part thereof to arch or curve slightly in cross section, as shown in Fig. 11, which arching would naturally cause the intermediate records to rest upon the bottoms of the pockets 36 and exert a tendency to rip the same. In order to obviate this disadvantage I provide slits 38 at the bottom edges of the pockets 36 so that the intermediate records are permitted to 75 rest upon the member 15 of the receptacle.

It will be clear that this envelop opens and closes with the receptacle so as to hold the records compactly and in substantial parallelism with each other when the parts 80 are closed, as well as in the relatively open fan-like arrangement, when the parts are open.

I believe that the construction and operation of this embodiment of my invention 85 will be clear from the foregoing description, when taken in connection with the drawings, but I may emphasize that this invention provides an arrangement for holding the records in a firm, compact and, preferably horizontal position when out of use, and for, by the exertion of very slight effort, exposing them in a relatively open position for examination, selection and withdrawal.

It will be understood that various changes may be resorted to, in the form, construction and arrangement of the several parts, without departing from the spirit and scope of my invention; and hence I do not intend to 100 be limited to the details herein shown and described except as may be included in the claims.

What I claim is:

1. Apparatus of the character described 105 comprising, a drawer and an articulated receptacle fitted to be carried by the drawer in closed position and in substantial parallelism therewith, and to be also carried by the drawer pendant therefrom in open position 110 and substantially at right angles thereto, said receptacle having its upper edges connected to the drawer.

2. Apparatus of the character described comprising, a casing, a drawer slidably 115 mounted therein, and a receptacle slidably mounted in the drawer and adapted to be moved from a housed position within the drawer to a pendant position without the drawer.

3. Apparatus of the character described comprising, a casing, a drawer slidably mounted therein, and an articulated receptacle slidably mounted in the drawer and adapted to be moved from a closed and 125 housed position within the drawer to an open and pendant position without the drawer.

4. Apparatus of the character described comprising, a drawer provided with grooves in its sides, and a receptacle provided with 130

means engaging said grooves, whereby the receptacle may be carried by the drawer in substantial parallelism therewith, and be also carried by the drawer at substantially 50 right angles thereto, said receptacle having its upper edges connected to the drawer.

5. Apparatus of the character described comprising, a drawer provided with grooves in its sides, and an articulated receptacle 10 provided with means engaging said grooves, whereby the receptacle may be carried by the drawer in closed position and in substantial parallelism therewith, and be also carried by the drawer in open position and at substantially 15 right angles thereto, said receptacle having its upper edges connected to the drawer.

6. Apparatus of the character described comprising, a drawer provided with grooves 20 in its sides, and an articulated receptacle slidably mounted in said drawer and provided with means on both of its side members engaging said grooves, whereby the receptacles may be carried by the drawer in closed position and in substantial parallelism therewith, and be also carried by the drawer in open position and at substantially 25 right angles thereto, and means for limiting the sliding motion of one part of the receptacle so as to assist in moving the same to open position and retaining it in said position.

7. Apparatus of the character described comprising, a casing, a drawer slidably 35 mounted therein, a receptacle slidably mounted in the drawer, means for limiting the sliding motion of the drawer in the casing, and means for limiting the sliding motion of the receptacle in the drawer.

40 8. Apparatus of the character described comprising, a drawer provided with grooves in its sides, and an articulated receptacle provided with means on both of its side members engaging said grooves, whereby 45 the receptacle may be carried by the drawer in closed position and in substantial parallelism therewith, and be also carried by the

drawer in open position and at right angles thereto, one of said grooves being shaped so that the receptacle will open automatically 50 under the influence of gravity.

9. Apparatus of the character described comprising, a drawer provided with grooves in its sides, and a receptacle provided with means engaging said grooves, whereby the 55 receptacle may be carried by the drawer in substantial parallelism therewith, and be also carried by the drawer at substantially right angles thereto, said means engaging said grooves being offset so as to hold the 60 receptacle, when open, in an elevated position with respect to the drawer.

10. Apparatus of the character described comprising, a drawer provided with grooves in its sides, and an articulated receptacle 65 provided with means on both of its side members engaging said grooves, whereby the receptacle may be carried by the drawer in closed position and in substantial parallelism therewith, and be also carried by the 70 drawer in open position and at right angles thereto, one of said grooves being longer than the other so that the receptacle may open as it moves to its position at right angles to the drawer.

75 11. Apparatus of the character described comprising, a drawer provided with grooves in its sides, and an articulated receptacle provided with means on both of its side members engaging said grooves, whereby the 80 receptacle may be carried by the drawer in closed position and in substantial parallelism therewith, and be also carried by the drawer in open position and at right angles thereto, one of said grooves being located 85 above the other for part of its length and projecting outwardly and downwardly into the path of the other, so that the receptacle will open automatically as it moves to its position at right angles to the drawer.

90 In testimony that I claim the foregoing as my invention I have signed my name this 15th day of September, 1919.

EDWARD BLAISE.
